UNITED STATES PATENT OFFICE.

HENRY S. DOSH, OF BALTIMORE, MARYLAND.

COMBINED BEDBUG-TRAP AND CASTER.

SPECIFICATION forming part of Letters Patent No. 317,322, dated May 5, 1885.

Application filed August 18, 1884. (No model.)

To all whom it may concern:

Be it known that I, HENRY S. DOSH, of the city of Baltimore, and State of Maryland, have invented certain Improvements in a Combined 5 Bedbug-Trap and Caster, of which the following is a specification.

This invention relates to the combination of a bowl to hold water, some liquid insecticide, or insect-powder, adapted for attachment to 10 the lower end of a bed-post, and a caster which is pivoted to the under side of the said bowl and adapted to turn in any direction independently thereof, as will hereinafter fully appear.

15 In the drawings forming a part hereof, Figures I and II are sectional views of the invention, and they differ only in certain details of construction, as hereinafter described.

A is a bowl, which in Fig. I is designed to 20 hold water or some liquid insecticide, and in Fig. II dry insect-powder. This bowl has a pin, *a*, whereby it is secured to the bed-post

B, and a flange, *b*, to keep it steadily in position. The flange *b* may have screws to hold it to the bed-post in Fig. II, if desired.

C is a caster of ordinary description, attached so as to be revoluble independently of the bowl A by means of a pin, *c*. This pin can be screwed or cast into the lower end of the bowl or formed as a part of it.

I do not claim, broadly, the combination of a bedbug-trap or an insect-guard and a caster, as such combination is not new; but

What I claim is—

A bowl for holding liquid or a dry powder adapted for attachment to the lower end of a bed-post combined with a caster which is secured to the under side of the said bowl and fitted to turn in any direction independently thereof, substantially as specified.

HENRY S. DOSH.
